UNITED STATES PATENT OFFICE.

FRANK KUHN AND JAY A. HAND, OF DETROIT, MICHIGAN, ASSIGNEES TO AMERICAN ELECTRICAL HEATER COMPANY, OF DETROIT, MICHIGAN, A CORPORATION OF MICHIGAN.

DESIGN FOR AN ELECTRICAL-HEATER GUARD.

52,328.

Specification for Design.

Patented Aug. 27, 1918.

Application filed June 15, 1918. Serial No. 240,241. Term of patent 14 years.

To all whom it may concern:

Be it known that we, FRANK KUHN and JAY A. HAND, both citizens of the United States of America, both residing at Detroit, in the county of Wayne and State of Michigan, have invented a certain new, original, and ornamental Design for Electrical-Heater Guards, of which the following is a specification, reference being had therein to

the accompanying drawings, forming part thereof, in which the figure is a perspective view.

We claim:

The ornamental design for an electrical heater guard, substantially as shown.

FRANK KUHN.
JAY A. HAND.
